(57) **CLAIM**

The ornamental design for a tape measure housing, as shown and described.

DESCRIPTION

FIG. 1 is a front-top perspective view of a tape measure housing showing my new design according to a first embodiment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a rear-bottom perspective view thereof;

FIG. 9 is a front-top perspective view of a tape measure housing showing my new design according to a second embodiment;

FIG. 10 is a front elevation view thereof;

FIG. 11 is a rear elevation view thereof;

FIG. 12 is a right side elevation view thereof;

FIG. 13 is a left side elevation view thereof;

FIG. 14 is a top plan view thereof;

FIG. 15 is a bottom plan view thereof;

FIG. 16 is a rear-bottom perspective view thereof;

FIG. 17 is a front-top perspective view of a tape measure housing showing my new design according to a third embodiment;

FIG. 18 is a front elevation view thereof;

FIG. 19 is a rear elevation view thereof;

FIG. 20 is a right side elevation view thereof;

FIG. 21 is a left side elevation view thereof;

FIG. 22 is a top plan view thereof;

FIG. 23 is a bottom plan view thereof; and,

FIG. 24 is a rear-bottom perspective view thereof.

(Continued)

The dashed broken lines in the figures illustrate portions of the tape measure housing that form no part of the claimed design.
